DIAGNOSIS OF ALLERGIES

William Holmes Gardner, West Palm Beach, Fla.

No Drawing. Application April 8, 1948,
Serial No. 19,892

2 Claims. (Cl. 167—78)

1

The present invention relates to the diagnosis of allergies in human beings, and has particular reference to a diagnostic compound and a new method for forming a preparation for diagnosing allergies in patients by determining patient reaction to allergenic substances under question in terms of action of the allergenic substances on the blood of the patient.

An object of the invention is to provide a novel diagnostic preparation for the purpose of making rapid and efficient determination of the reaction of a patient to various allergenic substances.

A further object is to provide a novel method for the determination of allergies by the administration of specific allergenic substances to the patient intradermally.

A further object is to provide a novel method for the determination of allergies in human beings by the use of blood samples, whereby the discomfort to the patient attendant the commonly practiced skin transfer test methods is eliminated.

A further object is to provide a method of testing for allergies whereby a series of tests for determining patient reactions to a plurality of different allergenic substances may be accomplished simultaneously, without resort to the commonly known "scratch test" where the skin of the patient is broken for the introduction of suspect allergenic substances.

A further object is to provide a novel method of testing for allergenic reaction wherein the results of the tests may be speedily and accurately determined in a manner permitting of accurate analysis and determination of a relative degree of patient sensitivity to the allergenic substance in question.

A further object is to provide a novel method for forming preparations for use in the diagnosis of allergies.

Yet a further object is to provide an agglutination test for the determination of allergies in human beings whereby the presence of sensitivity to certain substances such as foods, pollens, plants, inhalants and the like, may be determined by laboratory methods.

In accordance with the invention, the diagnostic preparations employed comprise cultures of colon bacillus which are specific to the foods, pollens, plants, inhalants, and the like which may comprise the source of the disturbance in the patient. The cultures may be employed to determine the presence or absence of any sensi-

2

tivity in the patient to the specific colon bacillus employed in forming the cultures.

In preparing the cultures, a specific colon bacillus is isolated from suspected sources of allergenic disturbances, such as a particular animal, plant, grass, tree, food, etc.

The *Bacillus coli* employed in the constitution of a specific diagnostic preparation may be found in any portion of a plant, tree, animal, or other substance in question. For example, when the suspect substance comprises pork or other flesh of the pig or hog, *Bacillus coli* specific to the source may be found in the flesh of the hog.

In some instances more readily available or 15 prolific sources of *Bacillus coli* may be found by investigation of the suspect substance. In the case of animal meats, for example, the liver was found to be the most prolific source of *Bacillus coli*. In the case of plants, the *Bacillus coli* 20 may be found in the fruit of the plant, the most prolific source comprising fruit in the green or unmatured state, and new growths on the plant. The same is true for weeds and grasses.

In the case of trees, such as for example the 25 orange or apple tree, *Bacillus coli* specific to these sources may be found in the green fruit, the most prolific source being newly formed green shoots containing a high concentration of the sap of the tree.

30 The pure culture is then incubated in a media suitable for growing colon bacilli. As an example of a specific preparation, where pork is the suspect substance, a small section of fresh hog liver is dropped into a standard media for growing *Bacillus coli* such as a sterile beef-peptone-lactose broth. The incubation in this broth may proceed for a sufficient time to procure an active, concentrated culture; as for example, a 35 period of forty-eight hours at 38° C. Incubation 40 may be accelerated or extended as desired in accordance with known laboratory techniques including variations in temperature, humidity, and the incubation media employed.

45 The culture is then inactivated, standardized and diluted, according to usual laboratory methods governing the preparation of culture for bacterial agglutination tests, such as the commonly known Widal test for typhoid. For example, a smear culture of the broth prepared above is 50 grown on sterile agar plates, being incubated for a suitable period, for example twenty-four to thirty-six hours at 38° C. Colonies of *Bacillus coli* developed are isolated and identified as such 55 by comparison with known cultural characteris-

tics, specific media, and microscopic examination, in accordance with known laboratory methods of determination and identification.

The pure specific *Bacillus coli* cultures selected are put into sterile beef-peptone-lactose broth and incubated at 38° C. for forty-eight hours or until the bacterial count reaches about 10,000,000 *Bacillus coli* per cubic centimeter.

The *Bacillus coli* is then inactivated by a suitable procedure such as autoclaving at twenty-two pounds pressure for fifteen minutes, more or less. The solution is then diluted with sterile saline solution, for example by the addition of equal amounts of saline solution, and is then ready for use. Greater dilutions may be desirable in certain instances.

The culture thus prepared, contains a colon bacillus having properties specific to the cultures prepared from the particular source, and thus permits of specific diagnosis of allergies based upon antibody reactions occurring in the blood of the patient.

A marked advantage of the diagnostic preparations of the invention resides in their adaptivity to use in blood agglutination tests, whereby all skin testing is eliminated and allergies may be determined by laboratory methods alone. In this case, the specific colon bacillus culture is combined with the blood serum of the patient whose allergies are to be determined. For example, one drop of the blood serum of the patient may be added to one drop of the *Bacillus coli* solution, placed in a sterile test tube and incubated for twelve hours. The solution is then dropped onto a glass slide and read microscopically to determine if agglutination has occurred, indicating a positive reaction to the *Bacillus coli* of the suspect substance. The degree of hypersensitivity of the patient to the substance is determined by the degree of agglutination or antibody reaction.

It is preferred to standardize the degrees of agglutination in terms of arbitrary readings of one, two, three or four plus, similar to the readings of the well known Widal test for typhoid, permitting of a standardized complete diagnosis of a particular allergy based upon anti-body reaction.

In carrying out the agglutination tests, blood serum of the patient must be employed. Whole blood or hemolized blood cannot be used.

The cultures prepared in accordance with the invention may also be administered to the patient intradermally. In such case, the cultures prepared and treated as above described preferably are filtered prior to injection between the layers of skin of the patient. Sensitivity of the patient to the specific colon bacillus or a positive reaction to the test, is shown by the usual skin reaction to intradermal tests, negative reactions showing no evidence of irritation or other skin disturbance.

Use of specific cultures of colon bacillus in

the determination of allergies, both by intradermal application and in bacterial agglutination tests, has been thoroughly checked for accuracy of result against the accepted passive transfer tests and clinically, as well as against each other. The results in all tests were found to coincide completely in terms of positive diagnosis and subsequent tests of suspect substances found to be positive against clinical symptoms appearing upon patient exposure.

The principles of the invention as set forth are capable of adaptation in accordance with known procedures by those familiar with this field, and accordingly the invention is to be limited only 15 as defined in the appended claims.

I claim:

1. A method of determining sensitivity of the patient to a suspect source of allergenic disturbance comprising isolating *B. coli* taken from the suspect source, culturing the *B. coli* from the suspect source to provide a colony of *B. coli*, inactivating the culture, and diluting the inactivated culture with sterile saline solution to make an extract having the allergenic characteristic of the suspect source, mixing the extract with the blood serum of the patient to incur agglutination in degree proportional to the degree of sensitivity of the patient to the suspect source, and observing the agglutination of the mixture to determine the sensitivity of the patient to the source of the *B. coli*.

2. A method of determining allergenic sensitivity of a patient to a source of allergenic disturbance comprising isolating *B. coli* taken from the suspect source, culturing the *B. coli* from the suspect source to provide a colony of *B. coli*, inactivating the culture, and diluting the inactivated culture with sterile saline solution to make an extract having the allergenic characteristic of the suspect source, withdrawing a sample of blood from the patient, separating the blood serum from the remainder of the blood in the sample, and mixing the extract with the blood serum, and observing the agglutination of the mixture to determine the sensitivity of the patient to the source of the *B. coli*.
